(57) CLAIM

The ornamental design for a photovoltaic shade system, as shown and described.

DESCRIPTION

A photovoltaic shading system made according to the invention may be used as a carport or similar shading and weather-protecting structure.

FIG. 1 is a top, front, left side isometric view of a photovoltaic shade system made according to the invention;

FIG. 2 is a top plan view thereof;

FIG. 3 is a front elevational view thereof;

FIG. 4 is an enlarged view of the end portion of the photovoltaic shade system of FIG. 3;

FIG. 5 is a rear plan view thereof;

FIG. 6 is an enlarged view of the end portion of the photovoltaic shade system of FIG. 4;

FIG. 7 is a bottom plan view thereof;

FIG. 8 is an enlarged right side elevational line drawing view thereof, the left side elevational view being a mirror image;

FIG. 9 is reduced sized, a bottom, front, left side isometric view thereof; and,

FIG. 10 is an enlarged portion of the structure of FIG. 7 illustrating an upper PV panel and a lower, curved protective panel spaced-apart and the end caps on the Z-portions removed to show more detail.
